BY *Howard P. Heiston*

UNITED STATES PATENT OFFICE.

CHARLES C. RANDALL, OF OLEAN, NEW YORK.

LINOTYPE-MACHINE.

1,253,726.

Specification of Letters Patent. Patented Jan. 15, 1918.

Application filed May 16, 1917. Serial No. 169,075.

To all whom it may concern:

Be it known that I, CHARLES C. RANDALL, a citizen of the United States of America, and resident of Olean, in the county of Cattaraugus, in the State of New York, have invented new and useful Improvements in Linotype-Machines, of which the following, taken in connection with the accompanying drawings, is a full, clear, and exact description.

This invention relates to certain improvements in linotype machines, and refers more particularly to an automatic slug adjuster as an attachment for machines having flat galley keys.

As is well-known to those skilled in this art, these slugs are cast in different lengths, depending upon the movement of the usual "adjusting bar" having a suitable handle or pin by which it may be adjusted by the operator, said slugs being cast to gravitate along an upright guide in transit from the casting mechanism to the galley, and while I am aware that various devices have been proposed to prevent overturning of the slugs in transit from the upright guide so that they shall be assembled upon the galley with their type edges uppermost, it is necessary in all of such devices with which I am familiar to shift the slug adjuster by hand to adapt it to slugs of different lengths, thereby necessitating a separate and distinct operation.

The primary object of my invention is to provide a simple and comparatively inexpensive slug adjuster which may be expeditiously and firmly attached to the linotype machine and operated automatically for slugs of different lengths through suitable connections with the adjusting bar by which the length of the slugs are determined, thereby eliminating one movement in the operation of the machine, and at the same time assuring the proper positioning of the slug adjuster according to the length thereof.

Other objects and uses relating to specific parts of the attachment will be brought out in the following description.

In the drawings—

Figure 1 is a perspective view of a portion of a linotype machine and my improved slug adjuster mounted thereon.

Fig. 2 is an enlarged detail sectional view of the upper portion of the same adjuster showing more particularly the cable-gripping device for holding the roller-supporting block against downward movement when set to any height within its range of adjustment.

Fig. 3 is a detail sectional view of the lower portion of the same device showing the manner of securing it to the under side of the right-hand galley bracket.

In order that my invention may be clearly understood, I have shown a portion of a linotype machine comprising a frame —A— carrying a vise jaw —a—, upon which is mounted a longitudinally movable adjusting bar —b— having a handle —c— by which it may be adjusted in the usual manner for controlling the length of the slugs.

Secured to the frame —A— is a galley-supporting bracket —d— carrying the usual flat galley —e—, upon which the slugs —f— are assembled with their type edges uppermost and also provided with the usual slug plate —g— co-operating with the upright portion of the galley bracket to guide the slugs in transit from the vise jaws to the galley.

The slug adjuster forming the subject-matter of my invention comprises a base block —1— secured by suitable fastening means, as screw —2—, to the under side of the galley bracket —d— and provided with a pair of vertical openings —3— for receiving a pair of upright rods —4— and —4'— which may be adjusted vertically in the openings —3— and are secured in their adjusted position by clamping screws —5—.

These rods, —4— and —4'— extend upwardly from the base block —2— in parallelism and at opposite sides of the bracket —d— just in front of the front edge of the upright portion thereof and are connected at their upper ends by a cross block —6— also

adjustable thereon and clamped thereto by screws —7—, thereby holding the upper ends of the rods in fixed relation.

The upper end of the rod —4— is provided with a horizontal extension —8— having a rearwardly offset portion —9— and a downwardly extending portion —10— adapted to engage the right-hand end of the vise jaw —a— to steady the upper ends of the upright rods —4— and —4'— against lateral movement in the direction of the pull of the operating cable for the slug-adjusting roller and its supporting block or carriage, presently described.

15 The base block —1— and upper block —6—, together with the upright bars —4— and —4'— constitute what may be termed the slug adjuster frame, the slug adjuster *per se* consisting of a block or carriage —11— slidable along and upon the guide rods —4— and —4'— and connected by means of a cable —12— and ferrule —13— to the hand-piece —c— of the adjusting bar —b—, said cable being passed around 20 grooved sheaves or rollers —14— and —15— which are mounted, respectively, upon the horizontal extension —8— and lateral offset —9— and serve to guide the cable in its lengthwise movement.

25 30 The ferrule —13— is loosely fitted over and upon the hand-piece —c— and may be readily detached or replaced when desired.

A roller —16— is loosely journaled horizontally upon a suitable hanger —17— 35 which in turn is mounted upon the sliding block or carriage —11— and is provided with a lengthwise slot —18— for receiving a clamping screw —19—, by which the roller may be adjusted vertically relatively to the 40 sliding block —11— and clamped in its adjusted position.

This roller —16— is supported between the upright guide rods —4— and —4'— directly in front of the front edges of the upright portion of the galley bracket —d— 45 for engaging the front type edges of the slugs and holding them against forward tilting movement or overturning in transit through the upright portion of said bracket, 50 thereby causing the slugs to gravitate to the galley with their type edges uppermost.

The intermediate portion of the cable is passed loosely through a vertical opening —20— in the upper block —6—, thus permitting the sliding block or carriage —11— 55 with the roller —16— thereon to move vertically as the adjusting bar —b— is moved horizontally by its operating member —c—, motion being transmitted from said bar to 60 the carriage —11— and roller —16— through the medium of the cable —12—.

The carriage —11— and cable —12— are so relatively adjusted that when the bar —b— is adjusted for slugs of a certain

length, the roller —16— will be similarly 65 and simultaneously adjusted for slugs of the same length.

A small cam lever —22— is pivotally mounted upon the upper block —6— at one side of the opening —20— for gripping the 70 cable against the opposite side of said opening to hold the carriage —11— and roller —16— against downward movement when set to a certain position, but is used only when the operator desires to set the type 75 matter in a measure narrower than that of the slugs on which the matter is being set, as for example in running around cuts.

In such case, it is necessary to set the vise jaws the full length of the slug first, and 80 while in this position, the lever —22— is adjusted to its gripping position to maintain the carriage —11— and roller —16— in position to receive the full length of the slug.

The vise jaws may then be moved back to 85 set the type matter on any shorter measure without affecting the adjustment of the roller —16—.

As the vise jaws of the machine are changed for various measures, the roller —16— and its supporting carriage —11— will be moved up or down as the case may require, thus automatically adjusting the roller —16— to required height for receiving and properly assembling the length of 95 slug being cast.

What I claim is:

1. The combination with the galley and adjusting bar of a linotype machine, of a 100 slug adjuster comprising a roller, a vertically movable support therefor, and connections between the adjusting bar and support for shifting said support with the roller thereon as the bar is shifted to different 105 positions.

2. The combination with the galley, slug plate and adjusting bar of a linotype machine, of a slug adjuster comprising an upright guide, a roller support movable along and upon the guide in proximity to the front edge of the slug plate, a roller on said support to contact with the front edges of the slugs, and means for transmitting motion from the adjusting bar to the roller support.

3. The combination with the galley, galley bracket and adjusting bar of a linotype machine, of vertically adjustable means for engaging the front edges of the slugs in transit through the upright portion of the galley bracket in transit to the galley, and connections between the adjusting bar and said vertically adjustable means for shifting said means as the adjusting bar is moved to different positions.

4. The combination with the galley, vise jaw, adjusting bar and a slug plate leading from the vise jaw to the galley, of an up-

right guide, a roller support movable along and upon said guide, a roller mounted upon the support in front of the guide to hold the slugs against overturning in transit from the vise jaw to the galley, a flexible connection between the roller support and adjusting bar for shifting the roller as the bar is adjusted, and means for gripping the connection to hold the roller support against

downward movement when the bar is adjusted in the direction to allow such downward movement.

In witness whereof I have hereunto set my hand this 9 day of May, 1917.

CHARLES C. RANDALL.
